UNITED STATES PATENT OFFICE.

HORACE S. CARLEY, OF HYDEPARK, MASSACHUSETTS.

BUOYANT SEAT OR COUCH.

SPECIFICATION forming part of Letters Patent No. 723,647, dated March 24, 1903.

Application filed May 14, 1902. Serial No. 107,301. (No model.)

To all whom it may concern:

Be it known that I, HORACE-S. CARLEY, a resident of Hydepark, Massachusetts, have invented a new and useful Buoyant Seat or 5 Couch, which invention is fully set forth in the following specification.

According to my present invention I utilize collapsible life-boats of the character shown in my Patent No. 627,979, dated July 10, 1900, in the construction of seats or couches for use on shipboard, at wharves or docks, and at other places where it is desirable to have such life-boats readily accessible for immediate use. In this manner I provide an attractive cover and protection to the life-boat and at the same time utilize to advantage the space occupied thereby. Furthermore, by employing in the construction of the seat or couch a removable pad or cushion constructed 20 of buoyant material I provide an additional means which may be thrown overboard and held onto by persons in the water to save themselves from drowning.

The invention will be best understood by 25 reference to the accompanying drawings, wherein—

Figure 1 is a perspective view of a complete seat or couch embodying my invention. Fig. 2 is a transverse sectional view thereof. 30 Fig. 3 is an under side detail view of part of the frame to which the cushion is attached, and Fig. 4 is a bottom plan view of said frame.

A is the annular float of a collapsible life-boat such as described in my patent afore- 35 said. I have not shown in the drawings the bottom, which in its collapsed condition occupies the space within the annular float. Upon float A rests a frame, preferably of elliptical outline corresponding to the shape of 40 the float, consisting of an elliptical rim b, a longitudinal slat or bar c, secured at its ends to the rim, and transverse slats or bars d, secured at their ends to the rim and at their middle to the slat c, which they cross.

45 e is wire-netting, preferably galvanized, tightly stretched and secured to the rim and slats by tacks or otherwise. Two cleats f are secured to the under side of each of the transverse slats d and the longitudinal slat c, in 50 such position as to engage the inner wall of the annular float and prevent longitudinal or lateral movement of the frame on the float. A

rope g, laced through openings in cleats f, may be gripped by persons desiring to hold to the buoyant cushion or pad when the same is 55 floating upside down in the water.

H is a cushion or pad filled with buoyant material h, such as granulated cork, and having a depending flap k around its edge, whereby the cushion is secured to the frame by 60 tacks or otherwise. Threads or wires l, looped through the cushion and wire-netting e and secured at their upper ends to buttons m, serve to upholster the cushion and as an additional means of securely attaching it to the 65 frame. An outer covering n over the seat and having a depending hood or curtain reaching to the floor or deck on which the float rests completely covers the whole and gives it the appearance of a couch or lounge. 70 Covering n is preferably loose, quickly removable, and made of waterproofing fabric.

As will be understood, in case it is desired at any time to use the life-boat the seat part may be readily removed by simply lifting or 75 throwing it aside. If desirable, the seat part may be thrown overboard and afford additional means for saving people from drowning.

What I claim is—

1. A seat or couch consisting of a life-boat having a continuous float of annular or similar form, a frame removably resting upon said float, and a pad or cushion resting upon said frame.

2. A seat or couch consisting of a life-boat having a continuous float of annular or similar form, and a buoyant pad or cushion removably supported by said float.

3. A seat or couch consisting of a life-boat 90 having a continuous float of annular or similar form, a frame removably resting upon the float, and a pad or cushion secured to and resting upon the frame.

4. A seat or couch consisting of a life-boat 95 having a continuous float of annular or similar form, a frame removably resting upon the float and composed in part of a stretched wire-netting, and a pad or cushion resting upon the frame and secured thereto by bindings 100 laced through the wire-netting.

5. A seat or couch consisting of a life-boat having a continuous float of annular or similar form, a frame removably resting upon the

float and composed in part of a stretched wire-netting, and a pad or cushion resting upon the frame and upholstered and secured to the frame by bindings passing through said pad or cushion and through the wire-netting.

6. A seat or couch consisting of a life-boat having a continuous float of annular or similar form, a pad or cushion supported by the float, and a covering over the pad or cushion and depending about the float.

7. A seat or couch consisting of a life-boat having a continuous float of annular or similar form, a frame removably resting upon the float, a pad or cushion resting upon and secured to the frame, and cleats or projections on the frame preventing lateral or longitudinal movement thereof on the float.

8. A seat or couch consisting of a life-boat

having a continuous float of annular or similar form, a frame removably resting upon the float and composed in part of a stretched wire-netting, a buoyant pad or cushion resting upon the frame and upholstered and secured to the frame by bindings passing through said pad or cushion and through the wire-netting, and cleats or projections on the frame preventing lateral or longitudinal movement thereof on the float.

In testimony whereof I have signed this specification in the presence of two subscribing witnesses.

HORACE S. CARLEY.
